United States Patent Office

Des. 181,966
Patented Jan. 28, 1958

181,966

CLOCK OR SIMILAR ARTICLE

Alexander J. Esch, Pittsburg, Kans.

Application December 19, 1956, Serial No. 44,253

Term of patent 14 years

(Cl. D42—7)

Fig. 1.

Des. 181,966

PAGE 2

Fig. 2.

Fig. 3.

Fig. 1 is a side perspective view of a clock or similar article, embodying my new design;

Fig. 2 is a front perspective view; and

Fig. 3 is another side perspective view thereof.

The side of the clock not shown is of the same appearance as the side shown. The back and top surfaces of the clock are substantially flat and plain.

I claim:

The ornamental design for a clock or similar article, as shown and described.
